AERATION SEPTIC TANK

James Estes and George A. Laird, Santa Ana, Calif.,
assignors to Aeration Septic Tank Company, Gunnison,
Colo.

Filed Sept. 28, 1971, Ser. No. 184,658

Term of patent 14 years

Int. Cl. D23—01

U.S. Cl. D23—2

FIG. 1.

FIG. 2.

FIG. 1 is a perspective view taken from the top, one side and one end of an aeration septic tank embodying our new design;

FIG. 2 is an elevation of the other side;

FIG. 3 is a view of the top thereof;

FIG. 4 is a view of the bottom thereof; and

FIG. 5 is an elevation of the other end thereof.

We claim:

The ornamental design for an aeration septic tank, as shown and described.
